UNITED STATES PATENT OFFICE.

CHARLES WIRT, OF PHILADELPHIA, PENNSYLVANIA, ASSIGNOR, BY MESNE ASSIGNMENTS, TO WIRT ELECTRIC SPECIALTY COMPANY, A CORPORATION OF MAINE.

INSULATING-JOINT.

1,040,971.

Specification of Letters Patent.

Patented Oct. 8, 1912.

Application filed April 24, 1907. Serial No. 369,888.

To all whom it may concern:

Be it known that I, CHARLES WIRT, a citizen of the United States of America, residing in the city of Philadelphia, in the county of Philadelphia, State of Pennsylvania, have invented certain new and useful Improvements in Insulating-Joints, of which the following is a specification.

My invention relates to insulating connections and is particularly useful with reference to insulating joints which are employed for supporting electric fixtures or combined gas and electric fixtures.

The general object of my invention is to provide a new and improved insulating joint, which is simple in construction, small in size and convenient in use, and which at the same time has great strength and durability.

20 To the above end my invention in general comprises an insulating joint consisting of a continuous outer shell, having end openings larger than the greatest diameter of the inner members, inner members therein, and 25 insulating material which is interposed between said inner members and the inside of said shell and which is subjected to a shearing strain when the device is in use.

My invention will be understood from the 30 following description and accompanying drawings, in which certain embodiments thereof are set forth.

In the drawings, Figure 1 is a side view of a joint embodying my invention, Fig. 2 is a 35 section thereof on the line A—A, Fig. 1, Fig. 3 is a section on the line B—B, Fig. 2, Fig. 4 is a side elevation of a modification, Fig. 5 is a sectional view of a modified form of outside member or shell, and Fig. 6 is a 40 side elevation of a modified form of inner member or pipe thimble.

In all of the views, like parts are designated by the same reference characters.

In the embodiment of my invention herein 45 illustrated I provide an outer member, casting or shell 1 and two inner members or pipe thimbles 2, 2. These inner members are of such a size that they are readily inserted in the shell. Between the shell and 50 the inner members is an insulating filling 3. Between the two inner members or pipe thimbles are disks or washers 4 of mica. The inner members or pipe thimbles 2, 2 are 55 screw-threaded as shown, for attachment of the joint to the pipe and for attachment of

the fixture to the joint. In Fig. 3 the embodiment shown is a gas joint, holes being bored through the closed ends of the thimbles and the disks being provided with central perforations as shown. In a blind joint, 60 unperforated disks will be employed and the thimbles will have no openings through them.

The inner wall of the outer member or shell 1 is provided with means to resist displacement at more than one angle, such means particularly resisting longitudinal and torsional shearing stresses. The outer walls of the inner members or pipe thimbles 2, 2 are provided with means for resisting 65 longitudinal and torsional shearing stresses. These means may be variously formed. In Figs. 1, 2 and 3, the outer member or shell 1 is provided with longitudinal corrugations 5. In addition to these there are transverse 70 corrugations 6. The shell shown in Figs. 1, 2 and 3, is made of sheet metal stamped to shape; consequently the corrugations 5 and 6 are reproduced upon the outside of the shell. Furthermore, as the metal is too 75 thin to have both longitudinal and transverse depressions occupy the entire surface of the outer member or shell, they are shown as each occupying separate portions thereof. The longitudinal corrugations 5 occupy the 80 center portion of the shell, while the transverse depressions occupy the extremities. In the modification shown in Fig. 5, the shell is formed of a malleable casting. The longitudinal depressions and projections 90 and the transverse depressions and projections cross one another and cover the entire inner wall of the shell. In the modification shown in Fig. 4, the longitudinal depressions are made by a series of bosses struck 95 out from the inside of the shell near the center. The transverse depressions are made by crimping in or bending in the edges of the shell.

As already stated, the inner members or 100 pipe thimbles 2 are provided with means to resist longitudinal and torsional shearing strains. These means, as shown, consist of transverse grooves 7 (see Fig. 6) extending throughout the whole, or nearly the whole, 105 of the length of the thimble, longitudinal grooves 8 crossing the transverse grooves and extending throughout the length of the thimble. As shown in the drawings, the longitudinal grooves are made somewhat 110

deeper than the transverse grooves. This is because they are not as close together as the transverse grooves.

The insulating filling 3 may be of any material which may be molded and has the necessary heat-resisting and insulating properties, together with the necessary mechanical strength. There is a variety of materials having the required property. One suitable for the purpose is Portland cement which when properly handled and given sufficient time to harden shows a reasonably high insulating quality. This insulating quality is increased if the cement has been properly impregnated to exclude moisture, which can be done without affecting its mechanical strength. The best material which I have so far found for this purpose is known by the trade name "Di-a-lite" which is a composition consisting mostly of flint. This material is capable of being molded in very soft condition and when hardened gives adequate mechanical strength, together with high insulating and heat-resisting qualities.

It will be noticed that, in the device just described, the shearing strain is taken entirely by the insulation. Many joints of this class are designed upon the theory that it is desirable that the metal part should overlap or interlock so that if the insulation be destroyed by heat or otherwise, nevertheless the metal parts will still hold together in such a way as to prevent the fixture from falling. This I believe to be a mistaken idea as the great danger in joints of this class is that of a gas leak, and in any of the conditions just specified, a gas leak at a joint where the insulation has become destroyed would be so dangerous that the danger of a falling fixture would be trifling by comparison. By my joint, should any leakage occur--and that I believe to be almost impossible--the fixture would be unsupported and would probably drop, thus giving notice in the most obvious manner of the failure of the joint.

Other insulating joints with which I am familiar are designed with flanges, shoulders, grooves or screw-threads upon their inner and outer members, which are well adapted to withstand longitudinal stress. I find that practically the greatest strength which is demanded in insulating joints is strength to resist torsion or turning strains.

A large proportion of these joints are used in fixtures which carry gas. A joint which may be gas-tight when first constructed will develop a leak if the parts are twisted even slightly, so long as intimate contact between the metal and insulating filling is broken. In my insulating joint, I do away with overlapping or interlocking parts, and the consequent objection.

A further advantage of the invention herein described, lies in the exterior metallic

shell which is fully insulated from the other parts. It has been found desirable in the art, in other insulating joints, to provide an exterior insulating coating for the sole purpose of keeping the conducting wires out of contact with the metal portions of the fixture. This outside insulating surface is easily broken or displaced through carelessness in handling or improper use of wrenches, etc. In my joint the essential parts are enclosed by the insulating layer or filling 3 and the surrounding metallic shell 1. The strength of construction is such that a pipe wrench or Stilson wrench may be used on the exterior surface of the joint and all the force necessary may be applied in order to make the screw joint snug.

I do not limit myself to the exact details shown, as the required tensile and torsional resistance may be obtained by the use of indent or bosses in the shell or on the inner members, or by stippling or milling these parts in many varieties of form, provided only the projecting surfaces are such as to give resistance to displacement at more than one angle.

I have shown my invention embodied in the form of a gas joint for combination fixtures, but it is apparent that it may be utilized with a blank joint for externally wired fixtures, or a hickey for internally wired fixtures, and with but obvious modifications, it may be employed in other forms of strain insulators of different types.

In accordance with the provisions of the patent statutes, I have described the principle of my invention, together with the apparatus which I now consider to represent the best embodiment thereof; but I desire to have it understood that the apparatus shown is merely illustrative and that the invention can be carried out in other ways.

Having now particularly described and ascertained the nature of my said invention, and the manner in which the same is to be carried out, what I claim and desire to secure by Letters Patent is:

1. An insulating connection having a continuous outer shell provided with end openings larger than the greatest diameter of the inner members, two inner members of a size to be readily insertible through the ends of said shell, and insulating material between said shell and said inner members, means on the shell and inner members, co-operating with the insulating material, to subject the latter to a shearing strain when the device is in use, substantially as set forth.

2. An insulating joint having a continuous outer shell provided with end openings larger than the greatest diameter of the inner members, two inner members of a size to be readily insertible through the ends of said shell, the outer surfaces of the inner members and the inner surface of the shell

having projections thereon, and insulating material between said shell and said inner members which is subjected to a shearing strain when the device is in use, substantially as set forth.

3. An insulating joint having a shell, two inner members therein, and an insulating filling between the inner members and the shell, the shell having longitudinal depressions near the middle portion and transverse depressions nearer the ends, the longitudinal depressions serving to resist torsional strains and the transverse depressions serving to resist longitudinal strains.

15 4. An insulating connection having a continuous shell provided with end openings, one at least being larger than the greatest diameter of the inner members, two inner members of a size to be readily insertible 20 through an end of the shell, and insulating material molded into the space between said shell and said inner members.

25 5. An insulating connection having a continuous shell provided with end openings, one at least being larger than the greatest diameter of the inner members, two inner members of a size to be readily insertible through an end of the shell, insulating material molded into the space between said shell and said inner members, and means on the shell and inner members, coöperating with the insulating material to subject the latter to a shearing strain when the device is in use.

30

latter to a shearing strain when the device is in use.

6. An insulating connection having a continuous shell provided with end openings, one at least being larger than the greatest diameter of the inner members, two inner members of a size to be readily insertible through an end of the shell, a disk of insulating material between the said inner two members, and insulating material molded into the space between said shell and said inner members.

7. An insulating connection having a continuous shell provided with end openings, one at least being larger than the greatest diameter of the inner members, two inner members of a size to be readily insertible through an end of the shell, a disk of insulating material between said inner two members, insulating material molded into the space between said shell and said inner members, and means on the shell and inner members, coöperating with the insulating material to subject the latter to a shearing strain when the device is in use.

This specification signed and witnessed this 27th day of March, 1907.

CHARLES WIRT.
